United States Patent Office

Des. 189,301
Patented Nov. 22, 1960

189,301

FIGURE ACTION TOY

Marvin I. Glass, 57 E. Ohio St., and Bayard C. Reed, both of Chicago, Ill.; said Reed assignor to said Glass

Filed Jan. 27, 1960, Ser. No. 59,181

Term of patent 14 years

(Cl. D34—15)

Figure 1 is a right side view of a figure action toy embodying our new design;

We claim:

The ornamental design for a figure action toy, substantially as shown.
